UNITED STATES PATENT OFFICE.

HENRY SCHOEBEL, OF HEMPSTEAD GARDENS, NEW YORK.

HOCK.

Application filed August 2, 1924. Serial No. 729,762.

To all whom it may concern:

Be it known that I, HENRY SCHOEBEL, a citizen of the Republic of Czechoslovakia, residing at Hempstead Gardens, in the county of Nassau and State of New York, have invented new and useful Improvements in Hooks, of which the following is a specification.

This invention relates to improvements 10 in eye-cooperating hooks and more particularly to hooks of this kind which are mainly composed of wire.

Among the objects of the present invention, it is aimed to provide a hook composed 15 of wire having loops formed at the receiving end of the hook to accommodate fastening means such as stitches, rivets, and the like, and which has also formed therein fastening means such for instance as a loop 20 at the closed end thereof to accommodate fastening means whereby the hook can be properly and securely attached at both ends.

The invention also contemplates the formation of a hook from a single piece of 25 wire, in which one free end thereof is secured between the main shanks of the hook and a loop formed in the wire adjacent to the free end of the wire disposed between such shanks so as to protect the wearer 30 against contact with such free end.

It is still further aimed in the present invention to provide a hook composed of a single piece of wire in which the rough free 35 ends of the wire are bent over to abut against portions of the wire, so as to permit making of such hooks without finishing off the free ends of the wire and yet insure the user of the same against contact with such rough free ends.

Still another object of the present invention is to provide a hook composed of a single piece of wire having loops for receiving 40 stitches, rivets, or the like at both ends thereof, which hook may assume the standard form in use today with respect to the turns of the wire, with the exception that at one end thereof an extra loop is provided.

Still another object of the invention is to provide a hook composed of one piece of 45 wire in which the main parts of the forming dies today in use may be used with but slight alteration therein, to produce a hook having stitch receiving or rivet receiving loops at both ends thereof.

Another object of the present invention 50 is to provide a combination wire hook and

riveting member in which the hook is provided with three rivet receiving loops and the riveting member composed of one piece and provided with three rivets formed in 60 the three loops of the hook.

These and other features, capabilities and advantages of the invention will appear from the subjoined detail description of one specific embodiment thereof illustrated 65 in the accompanying drawings, in which

Figure 1 is a plan view of a hook member;

Fig. 2 is a similar plan view with the hook portion broken off; 70

Fig. 3 is a side elevation of the hook member;

Fig. 4 is a rear view of the hook member;

Fig. 5 is a plan view of the hook member secured to a piece of cloth by a riveting 75 member;

Fig. 6 is a rear view of the hook member secured to a piece of cloth by a riveting member, and

Fig. 7 is a side elevation of the riveting 80 member detached.

The hook member forming the main part of the present invention consists essentially of one piece of wire and is adapted for use with eyes to form the ordinary hook 85 and eye combination so extensively used with dresses and wearing apparel in general. The wire member denoted generally by the reference character 1 has a body portion composed of a middle shank portion 2 continuing into a loop 3 in the same plane and then back adjacent to the shank member 2 to form a short straight shank portion 4 also extending in the same plane with the shank member 2 and loop 3 and then continuing 90 up through the bent portion 5 away from the plane of the shank 2 and loop 3 to form the hook portion by continuing into the shank member 6 which connects with the shank member 7 by the loop 8 disposed in a plane parallel to the plane of the loop 3 and shank 2. The wire 1 then bends down again through the bent portion 9 into the loop 10 disposed in the plane with the loop 3 and shank 2, the portion 9 bending over and 100 adjacent to the free end 11 of the shank 2 to inclose the same and thus guard the same against contact with the person of the wearer. The wire 1 from the loop 10 then continues into the elongated shank portion 12 adjacent 105 and parallel to the shank portion 2 and disposed in the same plane with the shank

110

portion 2 and loop 3 and terminating in the loop 13 disposed adjacent to the loop 3 and in the same plane therewith. The free end 14 of the loop 13 which forms the other 5 free end of the wire 1 extends toward, and abuts against, the shank 12 thereby to be enclosed and to protect the person of the wearer from contact with the same.

In the manufacture of these hooks, in 10 order to maintain the cost of the same at a minimum, the wire portions are cut off leaving the same rough and sometimes even a little jagged. If these free ends 11 and 14 were exposed and not protected against contact with the person of the wearer, obviously there would be danger of the same catching in the dress of the wearer or in the person of the wearer and causing damage and injury. With the loop 10 bent 20 down as illustrated in Figs. 1 and 2 to enclose the free end 11 and the free end 14 bent over to abut against the shank 12, obviously the free ends 11 and 14 are securely enclosed and guarded.

25 Of course the main object of the present invention is to provide the loop 10 whereby, a convenient fastening-means receiving portion is provided at the closed end of the hook by means of one and the same piece of wire. With the wire hooks heretofore in use, merely the loops 13 and 3 were provided and consequently the ingenuity of the dressmaker was frequently called upon to sew down the closed end of the hook. Frequently this was done by means of stitches sewed around the closed ends of the hook, and in some cases by providing a section of cloth or ribbon extending in the hook, and sewed to the material upon which the hook 35 is secured thus locking or anchoring the hook down in place.

With the loop 10 formed and positioned as it is in the present instance, provision is also made whereby the standard bending 45 tools in use today for forming wire hooks without the loop 10, can be used with slight alteration. It will be seen that the bending tool for the shank 2, loop 3, shank 4, bent portion 5, and shank portions 6 and 7 50 of the hook member will remain unaltered, and that only the bending tool or cam for bending or inserting the loop 10 is required, and that in addition to the foregoing the bending tool or cam for forming the shank 55 12 and loop 13 may remain as before.

In Fig. 7, there is shown a rivet plate member 18 having rivet members 15 and 16 struck up therefrom. As shown in Figs. 5 and 6 the wire hook portion is there shown 60 secured in place on a piece of material by a riveting member with the rivet portion 15 extending through the loop portion 10 and the rivet portions 16 extending through the loop portions 3 and 13. By means of this 65 riveting plate 18, stitches may be dispensed

with, and the wire hook member secured to the material with the material disposed between the riveting plate 18 and the wire hook portion, as shown.

As clearly shown in Fig. 3 the intermediate shank portion 2 may be provided with the usual hump portion 17 to cooperate with the hook portion to securely anchor the eye against accidental displacement.

It is obvious that various changes and 75 modifications may be made in the details of construction without departing from the general spirit of the invention as set forth in the appended claims.

I claim:

1. The combination with a wire hook member, of a one-piece riveting plate extending the full length and width of the hook member and the hook member having a plurality of loops disposed at the open end of the hook and at the closed end of the hook, and the riveting plate having rivet portions struck up therefrom to engage said loops to secure the hook members in place.

2. In a device of the class described composed of a single piece of wire, the combination with an intermediate shank portion, of a short longitudinal shank portion disposed adjacent said intermediate shank portion, an elongated longitudinal shank portion extending the entire length of the hook member in a straight line and disposed adjacent said intermediate shank portion, a hook portion extending up from said longitudinal shank portions, a loop portion connecting said elongated shank portion with said hook portion, a second loop portion connecting said short shank portion with said intermediate shank portion, and a third loop portion formed at one end of said elongated shank portion, the three shank portions and three loops being disposed in the same plane.

3. In a device of the class described composed of a single piece of wire, the combination with an intermediate shank portion, of a short longitudinal shank portion disposed adjacent to said intermediate shank portion, an elongated longitudinal shank portion extending the entire length of the hook member in a straight line and disposed adjacent to said intermediate shank portion, a hook portion extending up from said longitudinal shank portions, a loop portion connecting said elongated shank portion with said hook portion and disposed adjacent to the end of the closed end of the hook, a second loop portion connecting said short shank portion with said intermediate shank portion and disposed adjacent to one side of the open end of the hook, and a third loop portion formed at one end of said elongated shank portion and disposed to the other side of the open end of the hook, the three shank portions and three loops being disposed in the same plane.

4. In a device of the class described composed of a single piece of wire, the combination with an intermediate shank portion, of a short longitudinal shank portion disposed adjacent to said intermediate shank portion, an elongated longitudinal shank portion extending the entire length of the hook member in a straight line and disposed adjacent to said intermediate shank portion, a hook portion extending up from said longitudinal shank portions, a loop portion connecting said elongated shank portion with said hook portion and disposed adjacent to the end of the closed end of the hook, a second loop portion connecting said short shank portion with said intermediate shank portion and disposed adjacent to one side of the open end of the hook, and a third loop portion formed at one end of said elongated shank portion and disposed to the other side of the open end of the hook, the three shank portions and three loops being disposed in the same plane.

4. In a device of the class described composed of a single piece of wire, the combination with an intermediate shank portion, of a short longitudinal shank portion disposed adjacent to said intermediate shank portion, an elongated longitudinal shank portion extending the entire length of the hook member in a straight line and disposed adjacent to said intermediate shank portion, a hook portion extending up from said longitudinal shank portions, a closed end loop portion connecting said elongated shank portion with said hook portion, a second loop portion connecting said short shank portion with said intermediate shank portion, and a third loop portion formed at one end of said elongated shank portion, the wire extending from one of its free ends which opposes the elongated shank portion to form the third loop portion, then turning to the right to form the elongated shank portion, then again turning to the right to form the closed end loop portion, then turning to the left to close the closed end loop portion, then turning upward to form the hook portion, then turning downward and backward to form the short longitudinal shank portion, then turning to the right to form the second loop portion, and then passing between the two longitudinal shank portions to form the intermediate shank portion and terminating adjacent to the closed end loop portion.

HENRY SCHOEBEL.
